UNITED STATES PATENT OFFICE.

HUGH SANGSTER, OF BUFFALO, NEW YORK.

IMPROVEMENT IN HEAD-LAMPS FOR VESSELS.

Specification forming part of Letters Patent No. 38,764, dated June 2, 1863.

To all whom it may concern:

Be it known that I, HUGH SANGSTER, of Buffalo, in Erie county and State of New York, have invented certain new and useful Improvements in Head-Lamps for Vessels or Canal-Boats; and I declare the following description of my method of constructing the same to be sufficiently clear and exact to enable others skilled in the art to make and use my invention, and for that purpose reference is had to the accompanying drawings and the letters of reference marked thereon.

The same letters in Figures 1, 2, 3, 4, 5, 6, and 7 in said drawings represent similar parts in each.

The nature of my invention consists—

First. In a movable oil-pot so arranged or constructed that by means of a knob or thumb-piece placed outside of the lamp-case the oil-pot may be moved to or from the reflector and properly adjusted to the focus of the same without the necessity of opening the door of the lamp case or covering, and in so constructing and attaching the reflector to the lamp that it may be moved vertically, up or down, or caused to swing upon a center at its back by means of two knobs or thumb-pieces, which are placed outside of the lamp-case, thus giving complete control of the light without the necessity of opening the door of the lamp. It enables the boatman to adjust his light exactly to the focus of the reflector, or to cast the rays of light up or down.

Second. In an additional ventilation to the top of the lamp, consisting of four tubes covered with cones, for the purpose of allowing a larger and clearer passage for the hot air generated within the lamp-case; also, interposing between the looking-glass and the surface of the wings of the lamp a non-metallic substance, such as a thin sheet of board, (which is inclosed in a frame with the glass,) for the purpose of preventing the amalgamation of the tin on the wings of the lamp and the quicksilver on the looking-glass, and thus preventing the destruction of the silver on the glass which is attached to the wings to give an additional reflecting-surface for the light.

Fig. 2 in said drawings represents a front view of the lamp complete, showing the burner, chimney, oil-pot, ventilation-tubes, and the wings. A' and A are the wings, B the reflector,

C the chimney, D the burner, E the oil-pot, and F' the recess along which the lamp-pot slides. A² is the looking-glass, which is fastened in a frame, as shown at Fig. 6, and is attached to the lamp-wing by slipping up one end into or behind the slip or groove marked S. The end of the glass frame under the slip S is shown by the dotted lines, and marked T. The lower end is fastened by a thin strip of metal, which passes down into a groove, marked Q. This piece or fastening is marked R, and projects a little over the lower part of the frame and holds it to its place, as shown in the wing A. F and F' are the additional ventilation-tubes. The dotted lines show about the height required for the tubes inside of the case. R' represents the bail or handle by which the lamp is carried.

Fig. 1 is a side elevation of the lamp, showing the oil-pot, reflector, &c., also the arrangement outside of the lamp by which the oil-pot and reflector are moved. N and the arrows represent a case or box, within which the arrangement for moving the reflector and throwing the light up or down is made to swing at the point L. K is a piece of metal, which swings at the point L, and to which the reflector is easily attached or detached. This piece of metal is fastened to the case N by a wire, which passes through its center and through the sides of the case N. This wire or bolt is shown more clearly in Fig. 4 and Fig. 5, and is marked M. J represents a screw, which is bent, forming part of a circle, and is firmly attached to the piece K. H is a knob, which is made hollow, through which the screw J is made to work. This knob is held fast to the case N by two flanges, one on the outside of the case and one on the inside. They are marked J' and J². By turning this knob H to the right or left it works upon the screw J and moves the piece K and the reflector upon the center or joint L, thus giving the movement to the reflector, which throws the light up or down. The case N works in a slide up and down the back of the lamp, and is moved by the knob and screw G, which knob, on being turned, gives the vertical movement to the reflector. This knob G is held to its place by a double flange in a similar manner to knob H. I is a knob and screw, also held to its place by a double flange. It screws

onto a piece which is attached to the lamp-pot, and is marked I^3 . By turning this knob the lamp-pot is made to move to or from the reflector, in and along the recess F^3 . F^4 represents the feet upon which the lamp stands.

Fig. 3 represents a front view of the lamp, showing the way in which the grooves are made which hold the glass. U and U' represent two wires, which hold the wings when shut or closed. These wires also hold them when open; but, as they are in common use on canal boat lamps, they need not be described here. W and W' represent the groove for the glass. It is but a continuation of the top of the lamp, which is bent down and formed into the shape of a groove into which the glass is slid. The bottom groove, is made in as similar manner, being a part of the bottom of the lamp bent into the form of a groove, and is marked X and X' .

Fig. 7 represents a section through the lamp-door, and shows the manner in which the front glass is held to its place. The glass is made to slip upward in the slide or grooves in the door-posts, and is kept up by a piece, Y , which slips into a groove under the lower end of the glass, as clearly shown by the drawings.

In Fig. 2, A^5 is the recess, into which the

looking-glass frame is placed and fastened. This panel or recess is stamped into the tin.

What I claim as my invention, and desire to secure by Letters Patent, is—

1. The reflector, made movable for the purpose set forth by means of the two knobs H and G , and the piece K or reflector-holder, or their equivalents.

2. The lamp-pot so arranged that it may be moved, and its position changed inside of the lamp-case, by means of the knob I or its equivalent, on the outside of the lamp, for the purpose of adjusting it to the focus of the reflector.

3. The manner described of attaching the looking-glass and frame to the wings of the lamp, also the panel or recess which is stamped into the wing for its reception.

4. The cone-covered hot-air tubes, as described, and the grooves for the glass, bent and formed of the same pieces of metal as the top and bottom, as shown in Fig. 3, and lettered W W' X X' , also the manner of holding the front glass in the door to its place, as shown in Fig. 7, and by the piece Y .

HUGH SANGSTER.
